STARTING ATTACHMENT FOR ENGINE MANIFOLDS

Joe L. Holmes, Paris, Tex.

Application January 11, 1949, Serial No. 70,338

4 Claims. (Cl. 123—180)

1.

This invention relates to new and useful improvements and structural refinements in devices for facilitating the starting of internal combustion engines, particularly automobile engines, or the like, and the principal object of the invention is to facilitate starting by the prevention of flooding of the intake manifold by superfluous vaporization of fuel in the float chamber of the carburetor.

This object is achieved by the provision of an attachment for the intake manifold, an important feature of the invention involving what may be referred to as a vapor storage tank wherein superfluous vapor may accumulate after a heated engine is stopped, rather than being permitted to flood the intake manifold and render starting difficult, if not impossible.

Another feature of the invention involves the provision of an automatic valve in the attachment, which valve controls the rate of flow of vapor between the intake manifold and the vapor storage tank and thereby assures that vapors are withdrawn from the manifold at approximately the same rate as they are formed.

Some of the advantages of the invention reside in its simplicity of construction, in its adaptability to convenient installation on engines of various types, and in its adaptability to economical manufacture.

With the above more important objects and features in view and such other objects and features as may become apparent as this specification proceeds, the invention consists essentially in the construction and arrangement of parts as shown in the accompanying drawings, in which:

Figure 1 is an elevational view showing the internal combustion engine of an automobile and illustrating the invention in association therewith, and

Figure 2 is a fragmentary cross-sectional detail of the valve used in the invention.

Like characters of reference are employed to designate like parts in the specification and throughout the several views.

Referring now to the accompanying drawings in detail, the general reference character 10 designates a conventional internal combustion engine such as is used, for example, in an automobile 12, the engine 10 including an intake manifold 14 with which communicates a carburetor 16, the float chamber 18 of the latter, in turn, receiving its supply of fuel from a pump 20, as will be clearly apparent.

The invention involves the provision of an attachment for the intake manifold 14 to prevent

2.

flooding of the latter by superfluous vaporization of fuel in the float chamber 18 after the heated engine is stopped, which superfluous vaporization if permitted to occur, usually floods the intake manifold to such extent that starting is extremely difficult and when the engine is ultimately started, the fuel mixture is extremely rich and the engine operation correspondingly inefficient.

The starting attachment is designated generally by the reference character 22 and embodies in its construction a vapor storage tank 24 which is secured by a clamp or clamps 25 to suitable supporting structure, as exemplified in Figure 1, while a tube or conduit 28 communicates with the tank 24 and is connected in any suitable manner to the intake manifold 14, as indicated at 30.

An automatic control valve assembly 32 is provided between the conduit 28 and the tank 24, this valve assembly embodying in its construction a hollow, elongated body 34 having an end wall formed with an opening 36 which communicates with the tank 24 through the medium of a nipple 38, the end portions of the latter being screw-threaded in internally threaded sockets 40, 42, respectively, on the tank and on the valve body, respectively, as will be clearly apparent.

The remaining end wall of the body 34 assumes the form of a removable, screw-threaded adapter 44 to which is secured an end portion of the aforementioned conduit 28 by means of a coupling nut 46, the adapter 44 being formed with an axial bore or passage 48 whereby the conduit 28 communicates with the interior of the valve body 34.

The end wall of the body 34 surrounding the opening 36 constitutes a valve seat 50 which is engageable by a valve member assuming the form of a circular plate or disk 52, the latter being movably positioned in the valve body and being urged in engagement with the seat 50 by a suitable compression spring 54. It is to be observed that the valve member 52 is provided substantially in the center thereof with a metering aperture or orifice 56, the purpose of which will be hereinafter more fully described.

When the invention is placed in use and the engine 10, after becoming heated, is stopped, superfluous vaporization of fuel in the float chamber 18 of the carburetor 16 will "overflow," so to speak, into the intake manifold 14, but assuming the tank 24 to be empty, that is, at sub-atmospheric pressure, the excess vapors will be withdrawn from the manifold 14 through the conduit 28 and through the metering orifice 56

of the valve 32 into the tank 24. The orifice 56 is of a predetermined size so as to assure that the superfluous vapors pass from the intake manifold into the storage tank 24 at a slow rate of speed, only sufficient to withdraw the vapors from the manifold at the rate at which they are formed.

The engine 10 may be started without harmful effects from excess vapors in the manifold, and as soon as the engine is in motion, that is, as soon as sub-atmospheric pressure exists in the intake manifold 14, the valve member 52 will automatically become unseated and the vapors in the storage tank 24 will be permitted to swiftly return through the valve and through the conduit 28 into the manifold, for subsequent consumption by the engine. Needless to say, as long as the engine is in operation, sub-atmospheric pressure will exist in the tank 24 so that the tank is in readiness to receive excessive vapors as soon as the engine is again stopped.

Needless to say, in the absence of sub-atmospheric pressure in the intake manifold 14, the spring 54 is sufficiently strong to maintain the valve member 52 in engagement with the seat 50, as will be clearly apparent.

Finally, it should be explained that the removable adapter 44 facilitates convenient and expeditious access to the interior of the valve body 34 for the purpose of installing, inspecting or replacing the elements 52, 54.

It is believed that the advantages and use of the invention will be clearly apparent from the foregoing disclosure, and accordingly, further description thereof at this point is deemed unnecessary.

While in the foregoing there has been shown and described the preferred embodiment of this invention, it is to be understood that minor changes in the details of construction, combination and arrangement of parts may be resorted to without departing from the spirit and scope of the invention as claimed.

Having described the invention, what is claimed as new is:

- 5 1. An attachment for preventing flooding of an engine manifold by superfluous vaporization of fuel in carburetor, said attachment comprising a vapor storage tank, a conduit connecting said tank to an intake manifold, and automatic means for controlling the rate of flow of vapor through said conduit.
- 10 2. An attachment for preventing flooding of an engine manifold by superfluous vaporization of fuel in carburetor, said attachment comprising a vapor storage tank, a conduit connecting said tank to an intake manifold, and automatic means provided on said conduit for controlling the rate of flow of vapor from the manifold to said tank.
- 15 3. An attachment for preventing flooding of an engine manifold by superfluous vaporization of fuel in carburetor, said attachment comprising a vapor storage tank, a conduit connecting said tank to an intake manifold, and an automatic control valve provided on said conduit for effecting a relatively slow passage of vapor from the manifold to said tank and a relatively fast return thereof from the tank to the manifold.
- 20 4. The device as defined in claim 3 wherein said valve comprises a hollow elongated body having an end wall formed with an opening in communication with said tank, the end wall surrounding said opening providing a valve seat, a valve plate movable in said body and engageable with said seat, said plate being formed with a metering orifice, the interior of said body communicating through the medium of said conduit with the manifold, and resilient means in said body for engaging said plate with said seat in the absence of sub-atmospheric pressure in the manifold.
